METAL WINDOW CONSTRUCTION

Arthur H. Kiehl, Rocky River, Ohio, assignor to The F. C. Russell Company, Cleveland, Ohio, a corporation of Ohio
 Original application Mar. 8, 1957, Ser. No. 644,851, now Patent No. 2,916,112, dated Dec. 8, 1959. Divided and this application Sept. 18, 1959, Ser. No. 841,922
 7 Claims. (Cl. 20—11)

This application relates to window structure and particularly to a trim casing forming part of the window frame, and is a division of application Serial No. 644,851, filed March 8, 1957, now Patent No. 2,916,112, issued December 8, 1959.

The window frame structure includes a tubular trim casing that covers the interior of the wall opening inwardly of the frame and that is provided with a trim portion at right angles to the tubular portion for engagement with the interior of the building wall around the window opening. The tubular rectangular body of the trim casing is adapted to receive the inner edge portion of the window frame and is clamped to the inner edge of the frame by suitable means.

The trim casing is formed of four members of identical cross section provided with end portions that are adapted to interlock to permanently connect the four members to form the rectangular tubular casing, with the trim flanges coplanar and provided with mitered interfitting portions at the corners.

Reference should be had to the accompanying drawings forming a part of this specification, in which:

FIG. 1 is a vertical section through a window opening, the trim casing of the present invention and the head and sill of the window frame with which it is associated;

FIG. 2 is a horizontal section through a window frame jamb and a vertical trim frame member taken on the line indicated at 2—2 in FIG. 1;

FIG. 3 is a front elevation of an assembled trim frame;

FIG. 4 is a side elevation of the trim frame;

FIG. 5 is a fragmentary perspective of a corner of the trim frame, viewed as indicated at 5—5 in FIG. 4;

FIG. 6 is a side elevation of one of the trim frame sections;

FIG. 7 is an end elevation of a trim frame section viewed as indicated at 7—7 in FIG. 6;

FIG. 8 is a fragmentary end elevation of a frame section, viewed as indicated at 8—8 in FIG. 7;

FIG. 9 is a section taken on the line indicated at 9—9 in FIG. 8;

FIG. 10 is an end elevation of a trim frame section, viewed as indicated at 10—10 in FIG. 6;

FIG. 11 is a fragmentary elevation of a mitered end of the trim flange viewed as indicated at 11—11 in FIG. 6;

FIG. 12 is a fragmentary view showing the manner in which the frame sections are brought into interlocking relation at three corners of the frame;

FIG. 13 shows the frame sections in the positions they occupy during movement of the sections into interlocking relation at the fourth corner of the frame;

FIG. 14 is a fragmentary perspective viewed as indicated at 14—14 in FIG. 13, showing how the sections have moved into interlocking relations at the fourth corner to complete the frame assembly; and

FIG. 15 shows the sections just prior to the completion of the interlocking operation.

Referring to the accompanying drawings, the window of the present invention has a frame formed by jambs A, a head B and a sill C. The jambs A are of identical cross-sectional shape, being cut to length from extruded metal structural shapes formed from a metal such as aluminum. The head B which connects the upper ends

2

of the jambs A, is also an extruded structural shape and the same is true of the sill C which connects the lower ends of the jambs A.

In order to center the window frame in the wall opening 56 a series of springs 59 are mounted exteriorly of the jambs, head and sill for engagement with the sides, top and bottom of the wall opening 56. The springs 59 are in the form of curved sheet metal plates having curved outer end portions 60. The springs 59 are of short length and several of these springs may be spaced apart along the length of each jamb and along the length of the head and the sill. The inner end portions 62 of the springs 59 are curved on a longer radius than the outer end portions 60 and the inner free ends of the springs 59 are bent at 63 to provide inclined portions that project outwardly from the exterior of the frame when the springs are mounted on the frame.

The portions 62 of the springs 59 have wedging engagement with the interior of the wall opening 56 as the frame 20 is pushed into the opening and, since the outer end portions of the springs are backed by portions of the jambs A, head B and sill C, the engagement of the springs with the interior of the wall opening compresses the springs and forces the inner ends thereof inwardly toward the exterior of the window frame. The springs 59 serve to center the window frame in the wall opening prior to the attachment of the jambs A, head B and sill C to the building wall.

Inwardly of the window frame there is provided an 30 interior trim casing 64 that has a rectangular tubular portion formed by four walls 65 that covers the interior of the wall opening inwardly of the window frame, the casing having trim portions 66 extending outwardly from the walls 65 at right angles thereto and overlying the 35 interior of the building wall around the window opening. The trim portions 66 have reversely bent edge portions 67 provided with inturned flanges 68 that engage with the building wall. The rectangular tubular body within the wall opening composed of the four walls 65 is of a size 40 to receive the inner edge of the window frame. The casing 64 can be pushed into the window opening from the interior and the outer edge of the walls 65 will engage with the inclined edge portions 63 of the springs 59 to force the free ends of the springs 59 outwardly sufficiently 45 to permit the walls 65 to enter between the springs 59 and the exterior faces of the jambs, head and sill, the springs 59 serving to clamp the inner ends of the walls 65 against the edge faces of the window frame members.

The trim casing 64, which may be formed of sheet 50 steel and provided with a paint or enamel coating, has its sections formed so that they can be quickly and easily assembled and permanently joined together without the use of separate attached means such as screws, bolts or clips. The trim casing 64 is composed of four sections, 55 each including one of the flat body portions 65 that forms a wall of the tubular portion of the casing. Each section is provided at one end with a flange 194 that extends from the free edge of the body portion 65 to a point substantially midway between said free edge and the trim portion 66 of the section and that project from the interior face of the portion 65 at right angles thereto. The opposite end of each section is provided with a flange 195 projecting in the same direction as the flange 194 and extending from near the trim portion 66 to a point 60 substantially midway between the trim portion 66 and the free edge of the body portion 65. The end of the flange 195 adjacent the trim portion 66 may have its corner cut away to provide a beveled edge 196 and a short end shoulder 197. The ends of the trim portions 65 of each section extend past the side edges of the body portion 65 and overlap when the sections are joined together to provide a corner joint. At the end of the sec-

tion provided with the flange 194, the entire trim portion 66 projects past the end of the portion 65 to provide an attaching projection 198 of a length but slightly less than the width of the portion 66. The opposite end of each section is provided with a mitered projecting portion 199 having its outer end edge disposed at an angle 45° to the portion 66 of the section and extending to the inner end of the flange 195.

The face of the projection 198 has a triangular depression 200 which receives the mitered projecting portion 199 of the trim 66 to provide a mitered joint in which the external faces of the trim portions 66 are flush. The outer end of each projection 198 is provided with a toothed flange 201 projecting toward the flange 68 that engages the inner side of the portion 67 of the section with which the projection 198 engages. The sections may be permanently locked together by bending a portion of each flange 68 over the underlying toothed flange 201 in each corner of the casing.

In assembling the casing the sections are joined at three of the corners simply by inserting the flange 195 into the space between the flange 194 and the inner face of the integral trim portion 65 of the adjoining sections, with the sections disposed at an angle as shown in FIG. 12, then swinging the sections to the position shown in dotted lines in FIG. 12. The fourth joint is formed by springing the free ends of the sections to be connected at the fourth corner laterally one with respect to the other, to permit the free edge of one section 65 to be inserted beneath the flange 194 of the other section and the flange 195 of the first-mentioned section to be engaged with the exterior face of said other section as shown in FIG. 13. The flexibility of the body portions 65 of the sections permits the section having its free edge beneath the flange 194 of the other section to be moved laterally with respect to the other section to advance the flange 195 toward the flange 194 with the edge of the flange 195 sliding on the edge of the body portion 95 of the other section adjacent the projecting end of the trim portion 66 of said other section. As the flange 195 of one section moves toward the flange 194 of the other, the section so moved is bowed between the portion engaging the inner side of the flange 194 and the portion engaging the edge of the body portion 65 of the other section, causing increased pressure on the edge of the flange 195 due to the resiliency of the sheet metal. In order to relieve this pressure as the outer end of the flange 195 approaches the inner end of the flange 194, the bevel 196 is provided. During this movement the mitered end 199 moves toward the depression 200 in the projecting portion 198 formed to receive it. In the final portion of this movement, the flange 195 snaps into place engaging the mitered end 199 in the depression 200 and the end shoulder 197 of the flange 195 with the inner face of the trim portion 66 of the other section. With the flanges so positioned, the sections are firmly interlocked, but, in order to provide a permanent connection which will prevent springing apart of the overlapping projecting portions 198 and 192, an end portion of each flange 68 is preferably bent over into engagement with the toothed flange 201.

It is to be understood that in accordance with the provisions of the patent statutes, variations and modifications of the specific devices herein shown and described may be made without departing from the spirit of the invention.

What I claim is:

1. A trim casing comprising a tubular body portion of rectangular cross section and a marginal trim portion extending outwardly from said body, said casing having four sections each comprising a body portion forming one wall of said tubular body, an edge portion at each side thereof that engages the interior face of an adjoining section and an integral trim portion, the trim portion of each section having ends that project past the opposite sides of the body portion and that overlap at the corners 70

of the casing, the body portion of each section having an integral flange at each of its side edges that extends at right angles to said body portion and that overlies the exterior face of the body portion of an adjoining section to hold said sections at right angles to one another, and means interlocking the projecting ends of said trim portions at each corner of the frame.

2. A trim casing comprising a tubular body portion of rectangular cross section and a marginal trim portion extending outwardly from said body, said casing having four sections each comprising a body portion forming one wall of said tubular body, an edge portion at each side thereof that engages the interior face of an adjoining section and an integral trim portion, the body portion of each section having a flange at each of its side edges that extends at right angles thereto and that engages with the exterior face of an adjoining section to hold the sections at right angles to one another, the trim portion of each section having inturned edge portions and ends that project past the opposite side edges of the body portion thereof and that have overlapping engagement with the projecting ends of the trim portions of adjacent sections at the corners of the casing, said inturned edge portions having portions in interlocking engagement at each corner of said casing.

3. A trim casing comprising a tubular body portion of rectangular cross section and a marginal trim portion extending outwardly from said body, said casing having four sections each comprising a body portion forming one wall of said tubular body, an edge portion at each side thereof that engages the interior face of an adjoining section and an integral trim portion, the trim portion of each section having ends that project past the opposite sides of the body portion thereof, the projecting end of the trim portion of one section overlapping the projecting end of the trim portion of the adjoining section at each corner of the casing, the body portion of each section having a flange at each of its side edges that overlies the exterior face of an adjoining section, the flange at one edge of each section having its outer end in close proximity to the inner face of the projecting end of the trim portion of said adjoining section and the flange at the opposite edge of each section being spaced from the trim portion of the adjoining section a distance corresponding to the length of said first mentioned flange.

4. A trim casing comprising a tubular body portion of rectangular cross section and a marginal trim portion extending outwardly from said body, said casing having four sections each comprising a body portion forming one wall of said tubular body, an edge portion at each side thereof that engages the interior face of an adjoining section and an integral trim portion, the trim portion of each section having a flat exterior face, reversely extending edge portions and ends that project past the opposite sides of its body portion, one projecting end of each trim portion being mitered and the opposite end of the trim portion having an exterior face recessed to receive the mitered end of the trim portion of an adjoining section, the body portion of each section having a flange at each side edge engaging the exterior face of an adjoining section, the flange at the side edge past which said mitered end of the trim portion extends having an end closely adjacent said mitered end and the other of said flanges being near the free end of said body portion, said reversely extending edge portions of said trim portions being interlocked at each corner of the frame.

5. A trim casing comprising a tubular body portion of rectangular cross section and a marginal trim portion extending outwardly from said body, said casing having four sections, each comprising a body portion forming one wall of said tubular body, an edge portion at each side thereof that engages the interior face of an adjoining section and an integral trim portion, the body portion of each section having flanges at its side edges that project in the same direction and that engage with portions of the exterior faces of adjoining sections that are offset

longitudinally of said edges, the trim portion of each section having a face portion, an inturned edge portion spaced outwardly from the body portion that terminates in a reverse flange extending toward said body portion and ends that project past the opposite side edges of the body portion, the projecting end of one trim portion being received within the inturned edge portion and between the face portion and reverse flange of the trim portion of an adjoining section at each corner of the frame.

6. A trim casing according to claim 5 in which the body portion of each casing section has a single inturned flange at each of its side edges, one of said flanges being adjacent the integral trim portion and the other adjacent the opposite end of said body portion.

7. A trim casing that has a tubular body of rectangular cross section for reception in a wall opening and a trim portion extending outwardly from the body to cover a face of the wall around the opening and that comprises four sections each having a body portion that forms a wall of said tubular body, an integral trim portion and side edge portions that engage the interior faces of adjoining sections, and means for interlocking the sections

at each of the four corners of the casing upon assembly of the sections to hold the sections at right angles to one another and against relative sliding movements with respect to one another comprising a flange integral with each section at each edge of its body portion and projecting at right angles to said body portion for engagement with the exterior face of the body portion of the adjoining section to hold the sections at right angles to one another, the flange of one section being spaced from the trim portion thereof and the flange at the other section being adjacent the trim portion of said other section and received in the space between the flange and trim portion of the first mentioned section to hold the assembled sections against relative sliding movements.
